EXTENSION TABLE

Alvin M. Ellington, Watertown, Wis.

Application June 21, 1945, Serial No. 600,674

1. Claim. (Cl. 311—61)

This invention appertains to extension tables and like articles of furniture, and is an improvement over the table shown in my prior Patents No. 2,213,695 and 2,213,696 issued to me on September 3, 1940.

One of the primary objects of my present invention is to provide a table of the drop leaf type which can be opened or extended to various sizes to suit different conditions, and which will be of a strong and rugged character and capable of supporting a load without sagging, irrespective of whether the table is in its fully extended open position or not.

Another salient object of my invention is to provide novel means for carrying and associating intermediate supporting legs with the table in such a manner that said legs will always be in proper position for effectively and equally supporting the load and whereby the use of pivoted legs for the center of the table is eliminated.

A further object of my invention is to provide an extension table of the drop leaf type embodying a main table top and a pair of sliding end frames carrying the usual corner supporting legs, with novel means for associating one of the intermediate legs with certain companion sections of the extension table slide and the other intermediate leg with the main table top, the arrangement being such that the intermediate legs and the corner legs form substantially rigid triangular supporting bases for the end frames.

A further important object of my invention is to provide novel means for carrying one end drop leaf with the companion sections of the extension table slide which carries one of the intermediate legs, whereby a strong box-like frame will be had so that springing of the said drop leaf will be prevented incident to the continuous opening and closing of the table and so that said drop leaf can be slid slightly under the main table top, when the table is in its closed position for the conservation of space and to prevent the accidental swinging of said drop leaf.

A still further object of my invention is to provide an extension drop leaf table which will present an attractive appearance and which will occupy a minimum amount of space when the same is in its closed position and which can be opened to form a full size dining room table.

With these and other objects in view, the invention consists in the novel construction, arrangement and formation of parts, as will be hereinafter more specifically described, claimed and illustrated in the accompanying drawings, in which drawings:

2

Figure 1 is a side elevational view of my improved table showing the same in its closed position with the drop leaves in their lowered position, parts of the view being shown broken away and in section.

Figure 2 is a central longitudinal sectional view through the table showing the end frames pulled out for supporting the end drop leaves flush with the main table top, the section being taken substantially on the line 2—2 of Figure 5 looking in the direction of the arrows.

Figure 3 is a central longitudinal sectional view showing the table in an extended position and with a series of leaves associated therewith, the view being taken substantially on the line 3—3 of Figure 6.

Figure 4 is a top plan view of the table in its closed position, as shown in Figure 1, parts of the main table top being shown broken away to illustrate structural detail.

Figure 5 is a fragmentary top plan view of the table in its partially open position as shown in Figure 2, the main table top and the end leaves being shown broken away to illustrate structural detail.

Figure 6 is a top plan view of the table, showing the same in its open position and with a series of removable leaves in position, as illustrated in Figure 3, parts of the view being shown broken away to illustrate structural detail.

Figure 7 is an enlarged fragmentary detail sectional view taken on the line 7—7 of Figure 5, looking in the direction of the arrows, illustrating the novel means for associating one end drop leaf with certain companion sections of the table slide.

Figure 8 is an enlarged fragmentary detail sectional view taken on the line 8—8 of Figure 5, looking in the direction of the arrows, showing the means for interconnecting a drop leaf with one end sliding frame when the sliding frame is in its extended position and the drop leaf is in its raised position.

Figure 9 is an enlarged detail longitudinal sectional view taken on the line 9—9 of Figure 6, looking in the direction of the arrows and illustrating the means of associating the first removable leaf with the main table top.

Figure 10 is an enlarged fragmentary detail bottom plan view, also illustrating the means of disassociating the first removable leaf with the main table top, the view looking in the direction of the arrows, as shown by the line 10—10 of Figure 9.

Figure 11 is an enlarged fragmentary detail

longitudinal sectional view taken on the line 11—11 of Figure 6, looking in the direction of the arrows, illustrating the means of interconnecting the removable table leaves together.

Referring to the drawings in detail, wherein similar reference characters designate corresponding parts throughout the several views, the letter T generally indicates my improved table and the same includes a main table top 15 which is formed in one rigid piece. Associated with this table top are end frames 16 and 17, and these frames are slidably mounted relative to the main top.

The end frame 16 includes side skirt boards 18 and an end skirt board 19. These boards are rigidly connected together by a bottom reinforcing board 20 which extends transversely across the end frame. Corner legs 21 are rigidly secured to the bottom board 20 and to the skirt boards 18 and 19 by the use of suitable diagonally extending corner braces 22.

The end frame 17 is constructed similar to the end frame 16 and consequently the same includes side skirt boards 23 and an end skirt board 24. These boards are rigidly united by transversely extending bottom board 25. Corner legs 26 are rigidly connected to the side and end skirt boards 23 and 24 and to the bottom board 25 by means of diagonally extending corner braces 27. In lieu of the corner legs 21 and 26, the end sections 16 and 17 can carry pedestals similar to that shown in my prior Patent 2,213,695.

The table top 15 and end frames 16 and 17 are slidably connected by table slides 28 and 29 and each set of these table slides are arranged on opposite sides of the longitudinal center of the table. These slide sections 28 and 29 each include an innermost slide section 30 and these slide sections 30 are rigidly secured to the bottom board 20 of the end frame 16 by suitable fastening elements 31. The next adjacent slide sections 32 of the slide sets 28 and 29 are rigidly fastened to the main table top 15 by the use of suitable fastening elements 33. From the description so far, it can be seen that the end section 16 can be pulled out a limited distance relative to the main table top 15 and the slide sections 32 carried thereby. When the end frame 16 is pulled out relative to the main table top 15, the same forms a support for a drop leaf 34 which is hingedly connected to the bottom of the main table top 15 by strap or like hinges 35.

Each of the slide sets 28 and 29 include a plurality of slide sections 36, 37 and 38 and an end slide section 39. The end slide sections 39 are rigidly fastened to the end frame 17 by the use of suitable fastening elements 40, which can be rigidly fastened to the bottom board 25 of said end section 17. Hence this end section 17 can also be slid outward relative to the main table top 15 for supporting a drop leaf 41 arranged on the opposite side of the table from the drop leaf 34.

The drop leaf 41 is carried in a novel manner by the slide sections 38 of the slide sets 28 and 29. As best shown in Figures 3, 5 and 6, the slide sections 38 of the sets are rigidly united by a transversely extending hinge 42 of the piano type. The innermost leaf of this hinge is rigidly fastened to the mentioned slide sections 38 and the other leaf of the hinge 42 is rigidly fastened to the table drop leaf 41. Hence, this drop leaf is rigidly supported for an effective distance along its length. These slide sections 38 are also rigidly connected intermediate their ends together by a cross brace board 43 and the cross brace board

43, the hinge 42 and the slide sections 38 form a rigid box-like frame which forms an effective support for the drop leaf 41, and it is to be noted that due to the connection of the drop leaf with the slide sections 38 that the drop leaf can move independently of both the main table top 15 and the frame 17.

Attention is now directed to the novel means for supporting the intermediate part of the table. To form this support, I provide centrally disposed intermediate legs 44 and 45. The leg 44 is secured to a cap plate 46 and this cap plate is in turn rigidly fastened by securing elements 47 to the lower face of the main table top 15. By referring to Figures 1 and 2, it can be seen that this table leg is arranged at one side of the transverse center line of the main table top 15. The leg 45 is rigidly secured by means of fastening elements 48 to the cross brace 43, which unites the slide sections 38 of the slide sets together and hence this leg 45 forms a support for the slide sets and the hinge for the drop leaf 41.

As illustrated in Figure 1 of the drawings, when the table T is in its collapsed or non-extended position, the end frames 16 and 17 abut under the main table top and the side skirt boards 18 and 23 of the end frames can be provided with dowel pins and sockets so that a strong and neat structure will be had. The drop leaves 34 and 41 extend down over the ends of the end frames.

When it is desired to extend the table end to support the drop leaves flush with the table top, the drop leaf 34 is swung on its hinges 35 to a raised position and the end frame 16 is pulled out and the slide section 30 travel outwardly on the adjacent section of the table slide sets 23 and 29. Thus, the end frame 16 forms a support for the drop leaf. The drop leaf 41 is pulled out slightly with the slide section 38 so as to permit the upward swinging of said drop leaf. The end frame 17 is now slid outwardly with the slide sections 39 and these sections ride on the intermediate sections 38 of the slide sets. This end frame now forms an effective support for the drop leaf 41.

It is to be noted that the legs 44 and 45 are disposed so as to form an effective support for the center of the table and the leg 44 with the legs 21 provide a substantially triangular support for one half of the table while the leg 45 with the legs 26 form another triangular support for the other half of the table. The drop leaf 41 carries depending dowel or like pins 49 and these pins are adapted to be received in sockets 50 formed in the corner braces 27 of the end frame 17 when said frame is pulled out under the drop leaf. This interconnects the drop leaf 41 with the end frame 17 and consequently the slide section 38 and the leg 45 will be carried with the end frame 17 when the frame is pulled further away from the table top 15.

The end frame 17 is pulled further away from the main table top 15 when it is desired to extend the table to a further extent to form a full size dinner table, as shown in Figures 3 and 6. When this end section 17 is pulled outwardly, the intermediate sections 36, 37 and 38 slide on one another but the legs 44 and 45 remain in their set position relative to the corner legs 21 and 26.

After the end frame 17 is pulled out, any preferred number of removable leaves 51 can be placed on the slides between the main top 15 and the drop leaf 41. The leaf 51 which is placed adjacent to the main top 15 can have its lower 75 face provided with lock plates 52, which are

adapted to extend under the said main table top. Stop pieces 53 can be secured to the under face of the top 15 to act as guides for the members 52 and to prevent lateral slipping of this leaf relative to the main table top. The other leaves 51 can be interconnected together by the usual dowel pins and sockets as shown in Figure 11. The dowel pins are indicated by the reference character 54 in Figure 11.

From the foregoing description, it can be seen that I have provided an especially simple form of extension drop leaf table which possesses strong and rugged characteristics, and which is effectively braced so that wobbling of the table will be prevented. Stress is laid on the arrangement of the intermediate legs and the box-like frame carrying one of the intermediate legs and one drop leaf.

Changes in details may be made without departing from the spirit or scope of my invention, but what I claim as new is:

In an extensible table of the drop leaf type, a main table top, and frames movable under the table top and beyond the table top, ground supports rigidly connected with the frames, sets of table slide sections, means rigidly securing companion section of the slide sets to the table top, means rigidly securing one end frame to companion slide sections carried by the said first companion slide sections, a hinged drop leaf carried by one edge of the main table top adapted to be supported by said end frame when the same is

5 moved beyond the table top, a table leg rigidly secured to the main table top, means rigidly securing the other end frame to the companion outer slide sections of the table slide sets, a brace board rigidly connecting the companion slide sections which are adjacent to the outermost slide sections, a supporting table leg secured to said brace board, a piano hinge having one leaf rigidly connecting the outer ends of the last mentioned companion slide sections together, whereby said hinge and said brace board form, in conjunction with said last mentioned companion slide sections, a rigid box-like frame, a drop leaf supported by said piano hinge whereby said last mentioned drop leaf is moveable relative to the main table top and the end frames.

10 15 ALVIN M. ELLINGTON.
